DEEP WELL FISHING TOOL

Norman W. Alford, Houston, Tex.

Application January 24, 1948, Serial No. 4,131

2 Claims. (Cl. 294—102)

1 This invention relates to a deep well fishing tool. An object of the invention is to provide a tool of the character described adapted to be lowered into a well and engaged with an object stuck in the well and whereby said object may be removed from the well.

It is another object of the present invention to provide a fishing tool of the character described which may be readily disengaged from the stuck object, in case the latter cannot be removed, and the tool withdrawn from the well.

It is a further object of the invention to provide a fishing tool of the character described which may be easily released from a stuck object that cannot be pulled by rotation of the operating string while the latter is under tension.

Other objects and advantages will be apparent from the following specification which is illustrated by the accompanying drawings wherein:

Figures 1 and 2 show vertical, sectional views of the upper and lower ends, respectively, of the tool in engaging position.

Figure 3 is a cross-sectional view taken on the line 3—3 of Figure 1.

Figures 4 and 5 are vertical, sectional views of the upper and lower ends of the tool in released position and

Figure 6 is a side view partly in section of the complete tool engaged with the stuck object.

Referring now more particularly to the drawings wherein like numerals of reference designate the same parts in each of the figures, the numeral 1 designates the outer housing, as a whole.

Screwed into the upper end of the housing 1 there is a head 2 whose upper end is formed into a jaw clutch member 3.

The lower end of the housing is formed with a downwardly and inwardly tapering seat 4.

Extending axially through the outer housing there is a two part stem 5 which is threaded through a coupling 6, connecting sections of the outer housing, by means of coarse left hand threads 7.

On the upper end of the stem 5 there is a jaw clutch member 8 to which the operating string 9, which extends to the ground surface, is connected.

Suspended from the lower end of the stem 5 there is a gripping device 10 having the depending flexible arms 11 and on the lower ends of these arms there are the wedge shaped slips 12 whose inner sides are toothed.

2 A strong coil spring 13 surrounds the stem 5 and is interposed between the coupling 6 and the gripping device 10 and which tends to hold the slips 12 seated in the seat 4. The stem 5 has a swivelling connection with the gripping device.

On the stem 5 beneath the head 2 there is screwed a nut 14 and between said head and the nut there is a strong coil spring 15 which acts as a bumper upon upward movement of the stem.

It will be noted that the stem 5 is composed of two parts which are maintained against separation by a coupling sleeve 16 whose lower end is connected to the lower section of the stem 5 and whose upper end has an internal annular flange which surrounds the upper section of the stem 5 and on this upper section of said stem beneath said flange there is a head 17 which has a splined connection 18 with the coupling 16 so that the upper and lower sections of the stem 5 have a limited longitudinal movement but they rotate together.

In operation the device is assembled as shown in Figures 1 and 2 with the stem 5 screwed downwardly to its lower position in the coupling 6. This will allow the slips 12 to seat on the seat 4 and the tool, as thus assembled may be let down into the well and engaged over the upper end of the stuck object, such as a pipe or rod, 19.

The spring 13 will yield as may be required to allow the slips 12 to readily pass over the upper end of the stuck object 19 but said spring will urge said slips into their lower position around the stuck object.

An upward pull may then be taken on the operating string 9 and the stuck object may be pulled from the well bore.

During the attempt to remove the stuck object, if it proves to be difficult to remove, the string 9 may be lowered to allow the clutch member 8 to engage with the clutch member 2, as indicated in Figure 1, and the string 9 then turned to transmit torsion to the stuck object. 45 It is also to be noted that the stem 5 is tubular and fluid may be forced down through the fishing tool and circulate about the stuck object to loosen it.

If said stuck object cannot be pulled from the well bore tension may be kept on the string 9 to keep the clutch member 8 disengaged from the clutch member 3 and the operating string and stem 5 may then be turned to the right and this 55 will cause the thread 7 to move upwardly in

the coupling 6 thus pulling the jaws 12 upwardly out of the seat 4 and causing them to release the stuck object, which cannot be pulled, so that the tool may be removed from the well.

A preferred form of the invention has been shown and described for the purpose of illustration while the broad principle of the invention will be defined by the appended claims.

What I claim is:

1. A fishing tool comprising, a tubular housing having an inside downwardly tapering seat adjacent its lower end and having an internally threaded portion above the seat, a two part stem through the housing whose lower portion is formed with external threads to mesh with the housing threads, a gripping device depending from the stem and including contractile means arranged to be contracted by the seat, upon downward movement of the stem in the housing to grip an object in the tool, said stem being connected to the gripping device to move said device upwardly upon upward movement of the stem relative to the housing, clutch means on the upper part of the stem and on the housing engageable to cause rotation of the housing upon rotation of the stem and releasable to allow the stem to rotate independently of the housing and yieldable means acting against the stem and housing and normally tending to maintain said clutch means engaged and yieldable upon application of tension to the string to release said clutch means.

2. A fishing tool comprising, a tubular housing having an inside downwardly tapering seat adjacent its lower end, an inwardly thickened,

internally threaded coupling in the housing above said seat, a two part stem extended axially through the housing and whose lower portion is formed with external threads to mesh with said coupling threads, a gripping device depending from the lower end of the stem and having a swivelling connection therewith and including contractile means arranged to be contracted by said seat upon downward movement of the stem in the housing to grip an object in the tool, said stem being connected to the gripping device to move said device upwardly upon upward movement of the stem relative to the housing, clutch means on the upper part of the stem and on the housing engageable to cause rotation of the housing upon rotation of the stem and releasable to allow the stem to rotate independently of the housing, yieldable means normally tending to hold said gripping device on its seat and a coil spring acting against the stem and housing and normally tending to maintain said clutch means engaged, said spring being yieldable upon application of tension to the string to release said clutch means.

25 NORMAN W. ALFORD.
